ABSTRACT: A print ribbon mechanism for advancing a ribbon from a supply reel to a takeup reel and then reversing the direction of travel of the ribbon just before the ribbon is exhausted from the supply reel so that the functions of the two reels are reversed. The takeup reel is driven by a coaxial ratchet wheel which is rotated in discrete increments by a reciprocating and pivotable driving member. The takeup ratchet is restrained from reverse motion by a retaining pawl which is coupled to the driving member. In response to the detection of the near exhaustion of the ribbon from the supply reel a drive reversing lever is pivoted and an interposer portion thereof is placed in a coacting relationship with the reciprocating and pivotable drive member to cause said last named member to pivot in response to the next reciprocating drive motion thereof. In response to the pivoting of the drive member, the drive pawl which had been driving the takeup ratchet wheel is disengaged therefrom and the ratchet wheel which had been associated with the supply reel is now engaged by a drive pawl and the last named wheel becomes the takeup wheel. The detent member pivots in response to the pivotal motion of the drive member thereby withdrawing the detent from the wheel associated with the former takeup reel and associating the detent with the new takeup wheel.

PRINT RIBBON FEED STRUCTURE

This invention relates to a ribbon feeding and reversing mechanism and, more specifically, to a ribbon feeding and reversing mechanism associated with a print head carrier that moves relative to a stationary platen.

Typewriters and other similar printing mechanisms have been known for many years and, typically, they are provided with a fabric ribbon which is advanced past the printing position first in one direction and then the other. The printing ribbon is stored on a supply reel and is wound on a takeup reel after use. When the ribbon on the supply reel nears exhaustion, the function of the two reels are interchanged and the supply reel becomes the takeup reel while the takeup reel becomes the supply reel, thereby moving the ribbon in the other direction past the printing station. In typical prior art mechanisms, the supply and takeup reels were mounted in stationary positions at the sides of the typing machines. The present invention departs from the prior art devices in that the ribbon feeding and reversing structure is not stationary but is mounted with a moving carrier that moves a print head along the length of a stationary platen.

Printers which print in response to human control are seldom required to print at a rate faster than approximately 12 to 15 characters per second and then only for brief intervals while the operator types exceptionally familiar letter combinations. However, as printers were developed which were capable of responding to input coded signals and printing at much higher printing rates, it became necessary to develop improved features including an improved ribbon feeding and reversing mechanism.

In copending U.S. Pat. application Ser. No. 630,904, filed Apr. 14, 1967, by Edwin O. Blodgett, now U.S. Pat. No. 3,426,880 and assigned to the same assignee as the present application, there is disclosed the complete details of a high-speed serial character matrix page printer which is capable of printing at a much higher sustained printing rate than the conventional manual or electric typewriters. The ribbon feeding and reversing mechanism disclosed and claimed herein is suitable for use with the printer disclosed in the cited copending application, and/or with other printers which may be required to print on a character-by-character basis and/or with printers having a wide range of printing speeds.

Accordingly, a primary object of this invention is to provide an improved ribbon feeding and reversing mechanism.

Another object of the invention is to provide a ribbon reversing mechanism which reverses the direction of travel of the ribbon in response to the near exhaustion of the ribbon on the supply reel.

Another object of the invention is to provide a ribbon reversing structure which reverses the direction of travel of the ribbon during the time between printing operations.

It is another object of the invention to provide a ribbon advancing and reversing structure which is adapted for use with a print head carrier.

It is another object of the invention to provide a ribbon advancing and reversing structure which detents the takeup reel.

Other objects, features, and advantages of the present invention will appear as a detailed description thereof proceeds in the light of the drawing forming a part of this application and in which: FIG. 1, illustrates the ribbon feeding and reversing mechanism as viewed from the platen looking towards the ribbon feeding and reversing structure;

FIG. 2 is a partial cutaway view of the ribbon feeding and reversing structure as viewed from the top;

FIG. 3 is a cross-sectional view along lines 3-3 of FIG. 2;

FIG. 4 is a side view of the ribbon feeding and reversing mechanism; and

FIG. 5 shows the details of the ribbon feed at the printing position.

To aid the reader who may be interested in obtaining more details concerning the printer in which the present invention is illustrated, the above-identified FIGS. are identical to some of those in the cited Blodgett application. More specifically,

FIGS. 1-5 in the present application correspond to FIGS. 31, 30, 34, 32, and 33, respectively, of the cited Blodgett application. For convenience, identical item numbers are used in the present application and the cited Blodgett application.

The print head carrier includes a print ribbon support and feed structure 545 by which a print ribbon 544 is fed between ribbon supply and takeup reels 539 and passes across the end of the printing head nose block 189. The structure 545 is fabricated upon a base plate 521 terminated at its ends in upstanding L-shaped arms having an arm portion 522 perpendicular to the base plate 521 and an arm portion 523 spaced from and parallel to the base plate 521 and having a turned over edge providing a stiffening flange 523'. A tab 524 is struck out from the base plate 521 and machine screws 525 secure the arm portion 522 and tab 524 on the rear face of the carrier base casting 150 below the nose block 189 of the print head as shown in FIGS. 1 and 4. As illustrated in detail in FIG. 1, an aperture 526 provided in the end of each arm portion 523 and a coaxial aperture 527 provided in the base plate 521 support individual ones of two ribbon reel spindles 528 by means of a flanged bushing 529 seated in the aperture 526 and a flanged bushing 530 seated in the aperture 527. A ratchet wheel 531 having a hub 532 is secured by a pin 533 on each spindle 528 and each spindle 528 is rotationally secured in place on the base plate 521 by spaced washers 534 with intervening compression springs 535 and a C-spring 536 seated in a peripheral groove 537 provided in the end of each spindle 528 as shown. The upper end of each spindle 528 is provided with a radial pin 538 which engages the slotted end 539b of the hub 539a of a ribbon reel 539 placed on the spindle 528 and thus drivingly couples the spindle 528 and its associated reel 539.

A V-shaped bracket having a flat base portion 541 and arms 540 with turned-over edges to provide stiffening flanges 540', has the ends of its arms 540 riveted by rivets 540a to the ends of individual ones of the arm portions 523 as shown more clearly in FIGS. 1 and 2. Peripheral spaced edge portions of the bracket base portion 541 are turned up to provide plural spaced pedestals 542 upon which split cylindrical sleeves 543 are secured and over which the print ribbon 544 passes in its travel from one of the ribbon reels 539 to the other. The ribbon 544 is guided around and past the end of the print head nose block 189 by a unitary guide structure 545 having a configuration shown more clearly in FIG. 5. This guide structure 545 includes a mounting base portion 546 having an aperture 547 through which a machine screw 548 passes to secure the guide structure 545 on a projecting boss 549 fabricated on the underside of the nose block 189 as shown. The guide structure 545 has an upturned arm 550 of T-configuration having turned-back end portions 551 and turned-over edge tongues 552 spaced from the surface of the arm 550 to guide the print ribbon 544 along the length of the arm 550. The guide structure 545 includes a depending arm 553 having a tongue 554 struck therefrom and serving to deflect the edge of the paper, as it is being inserted on the platen 13 of the printer, pass the guide structure 545.

At a given time the print ribbon 544 is pulled by the one of the reels 539 serving as a driven takeup reel from the other reel operating as a freely rotating supply reel 539. Compression spring 535 provides a slight drag on the supply reel to maintain tension in ribbon 544. Each time the ribbon 544 on the prevailing supply reel 539 is nearing exhaustion, the direction of ribbon feed is automatically reversed in a manner presently to be described and the functions of the reels as takeup and supply reels 539 are reversed. In considering the reel drive arrangement, assume that the right-hand reel 539 as seen in FIG. 2 is currently driven to operate as the ribbon takeup reel. The drive of the right-hand reel 539 is accomplished by stepped rotational drive of its associated spindle 528. To this end, the teeth of the associated ratchet wheel 531 are engaged by the right-hand one of two end pawls 557 of a drive pawl member 558. The drive pawl member 558 is pivotally supported on a stud 559 carried by the arm 560, the pawl member 558 being spaced from the arm 560 by a spacer

bushing 561 (FIG. 4) carried by the stud 559 and extending through an aperture 562 (FIG. 2) of the base plate 521 formed by striking the tab 524 therefrom. One end of the arm 560 has an integral hub 563 (FIG. 1) by which it is pivotally supported on and in spaced relation to the base plate 521 by a base plate stud 564. The other end of the arm 560 extends between spaced guide bars 565, secured on the underside of the base plate 521, for guided motion over a range of reciprocal angular movements of the arm 560. Such reciprocal angular movement of the arm 560, accompanied by longitudinal reciprocation of the drive pawl member 558, is effected by the right-hand one of the print head pressure plate actuating shafts 210 (as seen in FIGS. 1 and 2) as the latter reciprocates through a range of angular motion during each character print operation as more fully described in the cited copending Blodgett application. To this end, the shaft 210 carries an arm 566 having a stud 567 for pivotal connection to one end of a link member 568. The opposite end of this link member 568 is pivotally connected by a stud 569 to the arm 560 near its free end as shown and is spaced from the latter by a spacer bushing 570 (FIGS. 1 and 2).

The drive pawl member 558 is provided with a central end stud 571 which anchors one end of the overcenter spring 572 having its opposite end anchored by a stud 573 of arm 592. Slide member 574 has a pair of elongated slots 575 (FIG. 2) by which it is reciprocally secured by headed rivets 576 on the base portion 541 of the V-shaped bracket having arms 540. Under the foregoing assumed conditions that the right-hand ribbon reel 539 in FIG. 2 is driven to operate as the takeup reel, the overcenter spring 572 biases the drive pawl member 558 clockwise (as seen in FIG. 2) about its pivot stud 559 to engage the right-hand pawl 557 with the teeth of the adjacent ratchet wheel 531. The reciprocal angular drive of the arm 560 and resultant reciprocal longitudinal drive of the drive pawl member 558 by the pressure plate actuating shaft 210 provides a one-tooth stepped rotational drive of the ratchet wheel 531 and reel 539. A pair of spaced detent members 577 are pivotally supported on and in spaced relation to the base plate 521 by base plate studs 578 and associated spacer bushings 579 (FIG. 4) and are mechanically connected by a link member 580 for concurrent pivotal motion on their pivot studs 578 and have free ends formed to provide detent pawls 581, and are connected by tension springs 582 to the drive pawl member 558 as shown. It will be evident that the positioning of the pawl member 558 to drive the right-hand ratchet wheel 531 as seen in FIG. 2 increases the tension of the left-hand spring 582 and thereby biases the right-hand detent pawl 581 into engagement with the teeth of the adjacent ratchet wheel 531 to maintain the latter stationary as the drive pawl 557 advances to engage the next succeeding tooth of the ratchet wheel 531. During driven longitudinal reciprocal motion of the drive pawl member 558, the latter is confined for guided motion between the link member 580 and a guide bar 583 which is secured to the base plate 521 but is spaced therefrom by spacer bushings 584 as illustrated in FIG. 3.

During the assumed drive of the right-hand reel 539 in FIG. 2 as the takeup reel, the overcenter spring 572 biases the slide 574 to the left to a position at which the right-hand end of the slots 575 of the slide 574 engage the headed rivets 576. The slide 574 has integral U-shaped arms 589 positioned at its ends and through which the ribbon 544 passes. When the ribbon 544 on the left-hand supply reel 539 becomes nearly exhausted, an eyelet (not shown) provided on the ribbon 544 moves into engagement with the left-hand arm 589 of the slide 574 and continuing takeup pull exerted on the ribbon 544 by the right-hand takeup reel 539 causes the ribbon eyelet to move the slide 574 to the right against the bias of the overcenter spring 572. A drive reverse lever 590 is pivotally secured on the base plate 521 by a rivet 591 and has an upstanding arm 592 of U-shaped configuration (FIG. 4) and loosely coupled thereto for initiating the pivotal motion thereof is a depending stud 573 of the slide member 574. The opposite end of said drive reverse lever 590 terminates in an

upstanding foot 593. As the slide member 574 is moved to the right as explained above, the depending stud 573 of the slide member 574 pivots the drive reverse lever 590 clockwise as seen in FIG. 2. Slot 573a in member 540 accommodates the motion of the depending arm 573. This pivotal motion of the lever 590 eventually positions its foot, or interposer member, 593 so that in response to the next longitudinal reciprocation drive motion of the pawl member 558 the interposer foot 593 is engaged by a step 594 provided on an enlarged O-shaped portion 595 of the pawl member 558 and causes the latter to pivot about pivot point 559 on the arm 560 and move the left-hand pawl 557 into engagement with the teeth of the left-hand ratchet wheel 531. It is biased into such engagement by the overcenter spring 572 which completes movement of the slide member 574 to the right where the left-hand end of its slot 575 engage the headed rivets 576. This pivotal motion of the pawl member 558 acting through the spring 582 disengages the detent pawl 581 of the right-hand detent member 577 from the teeth of the right-hand ratchet wheel 531. The ribbon feed is thereupon reversed; the left-hand ribbon reel 531 now operating as the takeup reel while the right-hand reel 539 operates as the supply reel. Upon near exhaustion of the supply ribbon 544 on the right-hand reel 539, an eyelet provided on the ribbon 544 engages the right-hand arm 589 of the slide member 574 and moves the latter to the left as seen in FIG. 2 with a consequent counterclockwise pivotal motion of the drive reverse lever 590 and eventual pivotal movements of the drive pawl member 558 and right-hand detent member 577 to effect driving engagements of the right-hand pawl 557 and detent pawl 581 with the right-hand ratchet wheel 531 thus again reversing the direction of the ribbon feed.

The print head assembly and the ribbon advancing and reversing structure are part of a subassembly having flanges 151 which allow motion of the subassembly on guide rail 153 all as more fully described in the cited copending Blodgett application.

While there has been shown and described what is considered at present to be the preferred embodiment of the invention, modifications thereto will readily occur to those skilled in the related arts. For example, modifications might be required in a type bar printer. It is believed that no further analysis or description is required and that the foregoing so fully reveals the gist of the present invention that those skilled in the applicable arts can adapt it to meet the exigencies of their specific requirements.

I claim:

1. In a print ribbon feeding an reversing mechanism, first and second reels serving as ribbon supply and takeup reels, respectively:
  - a first ratchet wheel associated with said takeup reel for rotating said takeup reel in response to the rotation of said ratchet wheel;
  - guide means for guiding the ribbon from the reel serving as a supply reel, past a printing station and to the reel serving as a takeup reel;
  - drive means supported for reciprocating, pivotal and longitudinal motion within a plane parallel to the plane of said first ratchet wheel and having a first pawl portion for engaging said first ratchet wheel and rotating said first ratchet wheel in discrete increments in response to each cycle of longitudinal motion of said drive means;
  - a drive reverse lever pivotally supported at a point intermediate to its ends and adjustable to first and second stable positions;
  - detecting means coupled to one end of said drive reverse lever for pivoting said drive reverse lever from one stable position to the other in response to the imminent exhaustion of the ribbon from said ribbon supply reel;
  - said drive reverse lever having at its other end an interposer for engaging said drive means and providing a fulcrum about which said drive means is pivoted in response to the first longitudinal reciprocation of said drive means after the pivoting of said drive reverse lever and

unitary spring bias means coupled to said drive means and said drive reverse lever for urging said drive means and drive reverse lever to pivot in opposite directions about their respective pivots.

2. The combination as set forth in claim 1 and including a second ratchet wheel, coplanar with said first ratchet wheel and which has the same association with the supply reel that the said first ratchet wheel has with the said takeup reel, and wherein said pawl portion of said drive means is disengaged from said first ratchet wheel and another pawl portion of said drive means engages said second ratchet wheel and rotates said second ratchet wheel in discrete increments in response to each cycle of longitudinal reciprocation of said drive means after said drive means has been pivoted by said drive reverse lever, whereby the functions of said first and second reels have been reversed so that they become takeup and supply reels, respectively.

3. The combination as set forth in claim 2 and including individual detent means associated with each of said ratchet wheels, and coupling means for selectively engaging the appropriate one of said detent means with the ratchet wheel associated with the takeup reel.

4. In a print ribbon feeding mechanism, first and second reels each having as associated ratchet wheel for rotating their respective reels in response to the driven rotation of the ratchet wheel, said first and second reels serving alternately and selectively as takeup and supply reels for a ribbon supply:

detecting means for detecting when the ribbon supply on the supply one of said reels has neared exhaustion; a drive reverse lever pivotally mounted at a point intermediate to its ends for motion between first and second stable positions;

coupling means coupling said detecting means and one end of said drive lever for moving said drive reverse lever

from one to the other of its stable positions each time said detecting means detects the near exhaustion of the ribbon supply on the supply reel; drive means including a first pawl for engaging and driving the ratchet wheel associated with the takeup one of said reels; reciprocating means for cyclically reciprocating said drive means; said drive means being coupled to said reciprocating means by a pivot for providing pivotal motion of said drive means relative to said reciprocating means; said drive reverse lever including at its other end an interposer extension for engaging a portion of said drive means which is to one side of the longitudinal reciprocal line of motion of said drive means for causing a pivotal motion of said drive means in response to the first longitudinal motion of said drive means after the pivotal motion of said drive reverse lever; and unitary spring bias means coupled to said drive means and said drive reverse lever for urging said drive means and said drive reverse lever to pivot in opposite directions about their respective pivots.

5. The combination as set forth in claim 4 wherein a second pawl is included in said drive means for engaging the ratchet wheel associated with the reel, which had been the supply reel, subsequent to the pivotal motion of said drive means whereby the reel, which had been the supply reel, becomes the takeup reel.

6. The combination as set forth in claim 4 and including detent means associated with the ratchet wheel associated with the takeup reel for preventing reverse rotation of the detented ratchet wheel.
